(57)

CLAIM

The ornamental design for a finger resistance band, as shown and described.

DESCRIPTION

FIG. 1 is a perspective view of a finger resistance band showing my new design;

FIG. 2 is a front elevational view thereof;

FIG. 3 is a rear elevational view thereof;

FIG. 4 is a right side view thereof;

FIG. 5 is a left side view thereof;

FIG. 6 is a bottom plan view thereof; and,

FIG. 7 is a top plan view thereof.

The broken line showing of portions of the finger resistance band forms no part of the claim.
